ABSTRACT: A molded cover and case are secured together to retain a printed timing circuit board therein and the assembly is inserted into the housing of a reed relay in the space normally provided for several reed switch modules and a connector module. A second board containing several resistors is housed in an external portion of the case. An auxiliary instantaneous pole unit is optionally provided and has plug-in connections to the printed circuit board, and all wiring terminals are of the pressure plate type.

PLUG-IN SOLID-STATE TIMER MODULE FOR CONVERTIBLE REED RELAY

CROSS-REFERENCE TO RELATED APPLICATION

This invention pertains to a timer module designed to be used in conjunction with a convertible reed relay of the type described and claimed in a copending application of Lawrence E. Van Horn, et al. Ser. No. 601,693, filed Dec. 14, 1966 and assigned to the assignee herein.

BACKGROUND OF THE INVENTION

This invention relates to timers for electrical relays and particularly to a solid-state timer module for a reed relay. Specifically the invention relates to a novel modular-packaging concept for the solid-state timer to permit easy attachment thereof to the reed relay.

The prior art solid-state timing devices for industrial control use have lacked the versatility and flexibility required of other industrial control devices. A typical timing device is panel mounted, approximately the size of a companion relay, has one or two output terminals which are fixed to either normally open or normally closed functions, is packaged in a relatively expensive potted housing and is electrically connected to the relay to be controlled by external wiring.

The timing device of this invention comprises a timer module having a relatively inexpensive, separable two-piece housing which traps a printed circuit board inside upon its assembly. The timer module connects directly to a convertible reed relay of the aforementioned type by plugging the timer into an opening in the relay normally occupied by several modular poles of the relay thereby requiring no additional panel area for the mounting of the timer. The electrical connections between the timer and relay are of the plug-in type and serve to connect the relay coil to the output of the timing circuit. Additionally, the relay has four remaining poles which are available as timed contacts and may be readily converted to either normally open or normally closed as desired. The timer may be provided with an optional pole for an instantaneous contact operation if desired, and provisions are available to readily connect a remote potentiometer into the control of the timing circuit to provide adjustment from a remote point.

SUMMARY OF THE INVENTION

It is therefore a primary object of this invention to provide a solid-state timer module for a convertible reed relay which is packaged in a housing designed to permit electrical and mechanical plug-in connection to the relay.

It is a further object of this invention to provide a solid-state timer of the above-mentioned type which may be readily altered to provide adjustment thereof by a remote point control device and may be provided with an auxiliary contact pole that is operated independently of the timing circuit.

These and other objects and advantages of the invention will become more apparent in the following specification and claims when read in conjunction with the drawings.

BRIEF DESCRIPTION OF THE DRAWINGS

FIG. 1 is a front view of the timer module of this invention inserted into a reed relay housing;

FIG. 2 is a side elevational view of the right-hand side of the timer module and reed relay housing of FIG. 1;

FIG. 3 is a front view of the reed relay housing with the timer module removed therefrom;

FIG. 4 is a top plan view of the timer module;

FIG. 5 is a longitudinal sectional view of the timer module taken generally along the line 5-5 in FIG. 4; and

FIG. 6 is an electrical diagram of one preferred solid-state timing circuit used in the timing module of this invention.

DESCRIPTION OF THE PREFERRED EMBODIMENT

With reference to the drawings, the timer module is shown in conjunction with the convertible reed relay of the afore-

mentioned copending application. While reference may be had thereto for a complete description of the relay, a brief description thereof follows to facilitate the understanding of the invention of this application.

5 The relay 2 comprises a hollow insulating enclosing case 4 riveted to a metal base plate 6 for securing the relay to a mounting panel. An electromagnet comprising a core 8, coil 10 and core pole extensions 12 and 14 is positioned within the insulating case 4 as shown in FIG. 2.

10 Insulating case 4 has upper and lower openings 4a and 4b, respectively, which extend across the front of the case and rearwardly along the respective upper and lower sides thereof. A central web 4c extends across the front of the case 4 between the opposite vertical sides thereof, separating the upper and lower openings 4a and 4b. Each of the openings 4a and 4b are divided into four pockets and each pocket may receive a pole unit module which is to be inserted into the opening, or pocket, from the front of the case.

15 As seen in FIG. 3, the lower opening 4b contains the maximum of four pole unit modules. Each of these modules contain a sealed reed switch member fixedly mounted therein and are therefore termed switch pole units. When inserted into the openings of case 4, the superstructures of the switch pole units serve to position the reed switch members in a definite operational relationship to the magnetic gas gap between core pole extensions 12 and 14 as depicted by the dotted line showing in FIG. 2. Energization of the coil 10 of the electromagnet establishes a magnetic flux across the gap between core pole

20 extensions 12 and 14 and through the reed contacts of the switch pole units to operate the latter. Although not specifically shown in the drawings, the reed contacts of the switch pole units are connected internally of each module to the respective wiring terminals shown on the exterior of each

three switch pole units and a coil pole unit. The timer provides an optional instantaneous operating pole, pressure plate wiring terminals and other variations generally accorded only the prior art pneumatic timing devices used in conjunction with dynamic relays.

Timer module 24 includes an insulating housing comprising a molded case 26 and a molded cover 28 secured together by screws 30 which take into threaded openings in the case 26 (FIGS. 4 and 5). While only one pair of screws 30 are shown at the left-hand end of the timer as viewed in FIGS. 4 and 5, a second pair of screws are provided at the right-hand, or outer end of the timer housing. A printed circuit board 32 is trapped within the cover 28 by the case 26 when the housing is assembled. Similarly, the shaft of a potentiometer extends through mating semicircular openings formed in the front surfaces of the case 26 and cover 28 to be trapped in position when the two housing portions are secured together by screws 30. While not specifically shown, the potentiometer case and timer housing may be assumed to be suitably keyed or provided with cooperating abutting portions to prevent rotational movement of the potentiometer case within the housing of timer 24.

The potentiometer shaft further extends through an opening in an insulating trim panel 34 and has a skirted knob 36 permanently secured to its outer end. Trim panel 34 has an index mark and the skirt of knob 36 is suitably provided with indicia to facilitate adjustment of the potentiometer. A knurled screw 38 is threaded into a tapped hole in the front of the timer housing adjacent the potentiometer knob 36. The underside of screw 38 is formed at a parallel angle to that of the skirt on knob 36 and a resilient washer 40 to is disposed about the screw shank to overlie the skirt on knob 36. Potentiometer knob 36 may be rigidly fixed at any setting by threading screw 38 inwardly to compress the washer 40 down tightly upon the skirt of the knob 36.

Molded case 26 has a hollow, rectangular boxlike portion 26a which is open on the side facing cover 28. Boxlike portion 26a extends along the upper exterior surface of relay housing 4 as seen in the drawings. A second printed circuit board 42 is secured within portion 26a against a boss therein and one recessed edge of the portion 26a by a screw 44. Board 42 carries the majority of the resistors utilized in the timing circuit, particularly those which produce high amounts of heat. The external positioning of portion 26a and board 42 provides for better heat dissipation from the resistors and keeps the heat-producing members away from the interior of the relay. While not shown in the drawings, wire connections are provided internally of the timer housing to connect the two printed circuit boards together.

Printed circuit board 32 has a pair of fingers 32a (FIG. 4) which extend rearwardly through an opening between the case 26 and cover 28. Each finger 32a rigidly carries a female connector clip 46 positioned for engagement with a respective blade terminal 22 of coil 10. As seen in FIG. 10, case 26 is provided with an insulating barrier which extends rearwardly between the connector clips 46 to prevent against short circuit between the connectors in operation of the device.

Insulating case 26 is provided with six wiring terminals 48, 50, 52, 54, 56 and 58, all of the pressure plate type. The terminals are arranged in two rows and are angled for easy frontal access in accordance with present industrial control device design requirements. Each terminal is riveted to the inside of the case and has an angled portion which extends through an opening in the wall. The angled portion carries the terminal screw and pressure plate thereon.

The timer module 24 is also provided with an auxiliary instantaneous operating pole unit if desired, and the same is shown in the drawings. The pole unit includes a molded insulating case 60 which attached to the case 26 by a screw 62 (FIGS. 4 and 5). The exterior configuration of case 60 is very similar to that of the case 26 in the area of the terminals and provides the timer with an appearance of continuity across the top surface. The case 60 is provided with a pair of terminal members 64 and 66 which are identical to the terminals 48-

—58 of the timer 24. A reed relay unit 68 is inserted within the case 60, positioned therein by ledges formed on the inner sides of the case. An interference fit between the case 60 and relay unit 68 serves to retain the relay unit within the case. The relay unit 68 is provided with wires which are soldered to the respective terminals 64 and 66 to connect the contacts of the unit to the external terminals. The coil terminals of the relay unit 68 are of the female plug-in connector type and are contained within the ends of the unit. As seen in FIG. 5, when the optional pole unit is mounted to the timer, the relay unit 68 operably receives plug-in connector pins 70 of printed circuit board 32.

The assembled timer module 24 is inserted into the opening 4a of reed relay housing 4. Timer cover 28 is provided with two projecting keys 72 and 74, the latter of which is rectangular, and will therefor only fit within the dovetail keyway adjacent the right-hand pocket to insure that the timer module is not inserted into opening 4b. Screws 76 are provided to hold the timer in place in the relay housing and a cover plate 78 is secured over the central web 4c to cover the keys and keyways. When the timer module is inserted as described, the connector clips 46 on printed circuit board 32 engage blades 22 of coil 10 to connect the coil to the timing circuit.

With reference to the circuit diagram of FIG. 6, the assembled relay and timer are connected to an AC source by wiring supply lines to the terminals 48 and 50 of the timer. Suitable internal wire leads connect these terminals to a full wave rectifier bridge 80 on printed circuit board 32.

The timing circuit is connected across a pair of lines leading from the output terminals of rectifier bridge 80. However, by suitable wire connections, terminals 52 and 54 are interposed in the positive polarity line to break the circuit and place it under the control of a remote switch 82 externally wired to the terminals 52 and 54 of the timer 24.

The timing interval of the circuit is varied by the setting of the potentiometer POT mounted in the front wall of timer 24 and operated by knob 36 as earlier described. The slider terminal of potentiometer POT is connected to the remainder of the timing circuit through terminals 56 and 58 and a jumper strap 84 connected therebetween. If it is desired to control the timing interval from some point remote from the panel on which the relay and timer are mounted, the jumper strap 84 may be removed and a remote potentiometer may be externally wired to the terminals 56 and 58.

The timing circuit itself is of a well-known type and the following description thereof will be brief, only certain essential elements being mentioned. When the AC supply source is connected to the timer, a positive voltage is applied to the base of an NPN transistor T1 to render that transistor conducting and in turn short out, or discharge a timing capacitor C1. When switch 82 is closed to begin the timing period, positive voltage is applied to the base of a second NPN transistor T2 to render it conducting and thereby short out the base current to transistor T1 to turn off the latter. Immediately capacitor C1 begins to charge up at a rate determined by the values of itself and the resistance setting of potentiometer POT. The voltage across capacitor C1 is applied to the base of a unijunction transistor UJT and it gradually builds up until, at the end of the desired time interval, it reaches a value sufficient to cause unijunction transistor UJT to fire. The latter causes a gate signal to be applied to a silicon controlled rectifier SCR which turns the latter on to connect the reed relay coil 10 to the circuit, thereby actuating the reed switch pole units 16 and 18. The coil 10 remains energized until the switch 82 is opened, at which time voltage is removed from the base of transistor T2 and reapplied to the base of transistor T1 to discharge the timing capacitor C1. It should be noted that when the optional pole unit is added to the timer, the reed relay unit therein is energized immediately upon closure of switch 82 to complete a circuit to terminals 64 and 66 and the external device connected thereto.

Thus there is disclosed herein a modular timer assembly which is readily connected to an industrial type reed relay,

such timer combining the advantages of solid-state circuitry and devices with the flexibility of prior art industrial control devices of the dynamic type. While a single preferred embodiment is disclosed, the timer module is susceptible of various modifications without departing from the scope of the appended claims.

We claim:

1. The combination with a convertible reed relay having an electromagnet mounted within an insulating housing, a pair of frontal openings in said housing on opposite sides of said electromagnet for each receiving a plurality of modular sealed reed switch pole units therein alongside said electromagnet, a plurality of said modular sealed reed switch pole units inserted in only one of said frontal openings to extend alongside said electromagnet in operational relationship therewith and having wiring terminal means on an exposed end of each of said modular switch pole units for connecting the reed switch contacts to respective load circuits, and plug-in electrical connector means on said electromagnet for connecting the latter to a supply source, said plug-in means being positioned within said insulating housing and in alignment with the other of said frontal openings; of a timer inserted into the said other of said frontal openings and comprising; and insulating case, a plurality of wiring terminals secured to said case, plug-in electrical connector means extending outwardly of said case and engaging with said plug-in means on said electromagnet, a solid-state timing circuit housed within said case, means connecting the input portion of said timing circuit to a pair of said wiring terminals for externally connecting said timer to a supply source, and means connecting the output portion of said timing circuit to said plug-in electrical connector means to pro-

vide time-controlled response of said electromagnet to operate a said plurality of modular sealed reed switch pole units.

2. The combination according to claim 1 together with 5 manually adjustable control means for varying the timing interval of said timer, said control means being carried by said case and having an operator portion thereof extending exteriorly of said case, means connecting the output portion of said control means to said timing circuit through an electrical series connection to a second pair of said plurality of wiring terminals, and means for externally joining said second pair of wiring terminals to complete the connection of said control means to said timing circuit.

3. The combination according to claim 2 wherein said insulating case includes a removable cover normally attached to said case and said timing circuit is formed upon at least one insulating board, and wherein said board and said manually adjustable control means are firmly secured within said timer case by cooperating portions formed on said case and cover to respectively trap said board and said control means therebetween upon attachment of said cover to said case.

4. The combination according to claim 2 together with an auxiliary pole unit module attached to said timer case, electromagnetic switching means carried by said auxiliary pole unit module, plug-in connector means electrically connecting the input of said electromagnetic switching means across the input of said timing circuit, and wiring terminals carried by said auxiliary pole unit module electrically connected to the output of said electromagnetic switching means.

UNITED STATES PATENT OFFICE
CERTIFICATE OF CORRECTION

Patent No. 3,562,595 Dated February 9, 1971

Inventor(s) William C. Swanson and David R. Stewart

It is certified that error appears in the above-identified patent and that said Letters Patent are hereby corrected as shown below:

Column 2, line 26: "gas" should be omitted
Column 2, line 72: "required dynamic industrial" should read
--required in dynamic industrial--
Column 3, line 55: "FIG. 10" should be --FIG. 4--
Column 3, line 70: "which attached to the case" should read
--which attaches to the case--
Column 4, line 36: "by the setting" should read --by changing
the setting--
Claim 1, Column 5, line 22: "of a timer inserted" should read
--of a timer module inserted--
Claim 1, Column 5, line 23: "and insulating case" should read
--an insulating case--
Claim 1, Column 5, line 24: "or wiring terminals" should read
--of wiring terminals--.

Signed and sealed this 29th day of June 1971.
